DISTRIBUTOR TIMING INDICATOR

Diamond W. Lum, Sacramento, Calif.

Application December 19, 1949, Serial No. 133,708

16 Claims. (Cl. 177—311)

1

This invention is directed to, and it is an object to provide, a novel signal device for warning the operator of an internal combustion engine, having an electrical ignition system, when the distributor of the latter is not properly adjusted and is working out-of-time; the invention being especially designed, but not limited, for use on motor vehicles.

Another object of the invention is to provide a warning signal, for the purpose described, which functions when the engine is in operation, and thus gives a warning to the operator immediately when an out-of-time condition exists or occurs in the distributor, whereby an adjustment may be made before engine damage or undue waste of fuel results.

An additional object of the invention is to provide an out-of-time warning signal which includes one electrically energized indicator on the instrument panel of the vehicle to warn the operator of improper engine timing; there being another electrically energized indicator adjacent the distributor adapted for use as an aid to a mechanic in making a proper timing adjustment of the distributor.

A further object of the invention is to provide a device which facilitates setting of the distributor to a proper position of adjustment; the latter being indicated by the cessation of operation of the out-of-time indicators; the latter preferably being electric signal lights whereby the out-of-time warning signal is visual.

It is also an object of the invention to provide an out-of-time warning signal designed for ease and economy of manufacture and installation.

Still another object of the invention is to provide a practical and reliable out-of-time warning signal, and one which will be exceedingly effective for the purpose for which it is designed.

These objects are accomplished by means of such structure and relative arrangement of parts as will fully appear by a perusal of the following specification and claims.

In the drawings:

Fig. 1 is a plan view of a distributor embodying the invention; the distributor cap being removed, and the parts shown in the positions occupied thereby between firing points.

Fig. 2 is a similar view, but shows the parts, in their positions at the moment of firing of the distributor, when the timing adjustment is correct.

Fig. 3 is a view as in Fig. 2, but shows the positions of the parts, at the moment of firing, when the distributor is out-of-time.

2

Fig. 4 is a fragmentary elevation of the distributor showing particularly the adjustable mount for the contact units of the warning signal device.

5 Fig. 5 is a diagram of the signal circuit at the moment of firing of the distributor when the latter is in-time.

Fig. 6 is a diagram of the signal circuit at the moment of firing of the distributor when the latter is out-of-time.

10 Referring now more particularly to the characters of reference on the drawings, the invention is embodied in an ignition distributor which includes a hollow, distributor body 1 of rotatably adjustable type; the distributor having a vacuum responsive control unit 2 associated therewith, which unit is connected to a vacuum conduit 3, as is conventional. The vacuum responsive control unit 2 acts to retard and advance the distributor for low and high engine speeds, respectively.

15 The distributor shaft 4 extends upwardly through a fixed housing 5 axially into the distributor body 1 and projects through a base plate 6 in the body 1.

20 The distributor shaft 4 is fitted, above the base plate 6, with a cam 7 which works a breaker arm 8, and the latter in turn actuates breaker points 9, one of said points being on the breaker arm 8 and the other on a bracket 10. Additionally, the distributor shaft 4 is fitted, above the cam 7, with a distributor rotor 11. The numeral 12 indicates a condenser mounted on the base plate 6 and connected by a lead 13 to an input terminal 14. The distributor body 1 normally has a distributor cap 15 removably secured thereon.

25 The above described distributor is of generally conventional type, and the present invention, as applied thereto, is constructed as follows:

30 A dielectric mounting strip 16 is secured to the bracket 10 and projects therefrom in a generally outward direction, being fitted at its outer end with another bracket 17. A separate pair of contact points 18 are provided between the breaker arm 8 on the side opposite the points 9 and the bracket 17; said contact points 18 thus being disposed to close each time that the breaker points 9 open.

35 40 Below the base plate 6 the distributor shaft 4 is fitted with a radial arm-type rotor 19 having a roller 20 on its outer end. A pair of elongated, leaf-spring type switch units, indicated at 21 and 22, are mounted on a platform 23 exteriorly of 45 50 55 the distributor body 1 and project from said plat-

form into said body through a circumferential slot 24.

The switch units 21 and 22 are disposed in adjacent but spaced relation circumferentially of the body 1, and each of said units includes one arm thereof projecting into the rotary path of the roller 20, whereby with each revolution of the rotor 19 the switch units 21 and 22, which are normally open, are successively engaged and closed.

The platform 23 is an integral part of a bracket 25 attached in normally fixed position exteriorly of the body 1 by means of a saddle plate 26 secured by screws 27 to the distributor shaft housing 5; the screws 27 extending through elongated adjustment slots 28 which permit the bracket 25, together with the switch units 21, to be adjusted circumferentially of the distributor.

The platform 23 carries a pointer 29, and the bracket 25 is adjusted so that such pointer is radially aligned with the rotor 19 when the latter is disposed centrally between the switch units 21 and 22, as shown in Fig. 2; this being an in-time position of the distributor, and at which time the cam 7 has acted on the bracket arm 8, opening the points 9 and closing the points 18. In other words, as long as the distributor is in-time the roller 20 of the rotor 19 will be disposed in an intermediate position between the switch units 21 and 22, as in Fig. 2, when the corresponding "firing point" of the cam 7 works the breaker arm 8.

However, if the distributor is out-of-time the roller 20 of the rotor 19 will be in closing engagement with one or the other of the switch units 21 or 22 as the distributor reaches said firing point, as shown in Fig. 3, and at which time the contact points 18 are simultaneously closed upon opening of the breaker points 9.

The above switching arrangement is employed, to give an automatic signal to indicate the out-of-time condition, by means of the circuit shown in Figs. 5 and 6.

The main circuit lead is indicated at 30 and extends from the storage battery 31 to connection with one of the contact points 18; such lead 30 having a pair of electric signals 32 and 33 interposed in parallel branches 30a and 30b. The signals 32 and 33 are preferably lights, with the signal 32 on the instrument panel of the vehicle and the signal 33 under the hood adjacent the distributor.

The other contact point 18 is connected to a lead 34 which includes branches 35 in parallel; said branches being grounded, as at 36, to complete the circuit relative to the battery 31; the latter being grounded, as at 37.

The switch units 21 and 22 are interposed in corresponding ones of the circuit branches 35 whereby said switch units are in parallel in the circuit but are connected in series relation to the switch comprised of the contact points 18.

When the engine is running with the distributor in-time, the roller 20 lies between the switch units 21 and 22 when the corresponding firing action of the distributor occurs, with resultant closing of the contact points 18. Thus, even though the contact points 18 are closed at this moment the signal circuit is not energized, for the reason that both of the switch units 21 and 22 are open. (See Fig. 5.) However, if the engine is running with the distributor out-of-time, the roller 20 will engage and close one or the other of the switch units 21 or 22 at the mo-

ment that the contact points 18 close, as hereinbefore described. When this occurs the circuit is completed as contact points 18 and one of the switch units 21 or 22 are closed in series relation to each other, resulting in energization of the circuit and actuation of the signals 32 and 33, said signals blinking on and off as the rotor 19 traverses its path of movement.

Operation of the signal 32 indicates, to the operator of the vehicle, that the distributor timing is not correct, and thus affords opportunity for adjustment of the distributor before damage occurs, or before undue fuel waste results.

The signal 33 adjacent the distributor is for the purpose of permitting the mechanic to have an at-hand indication when the distributor, under adjustment, is set to correct position; i. e. as long as the distributor is out-of-time the signals 32 and 33 will continue to blink, but when the adjustment is proper such signals will no longer function. The signals 32 and 33 are preferably electric lights, as previously indicated.

The above described warning signal provides a very practical and reliable device for automatically indicating when the ignition distributor of an internal combustion engine is not in proper adjustment; the device standing ready at all times, when the engine is running, to indicate an out-of-time condition.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention as defined by the appended claims.

Having thus described the invention, the following is claimed as new and useful, and upon which Letters Patent are desired:

1. An out-of-time signal device for an internal combustion engine including an adjustable ignition distributor having distributor shaft actuated breaker points, an electric signal, an energizing circuit for the signal, a switch in the circuit, means responsive to actuation of the breaker points arranged to close the switch, a separate switch in the circuit, and means actuated by the distributor shaft arranged to close the separate switch simultaneously with said first named switch only when the distributor is out-of-time.

2. A signal device, as in claim 1, including another electric signal in the circuit; the device being mounted on a motor vehicle with one signal adjacent the operator's station and the other signal adjacent the distributor.

3. A signal device, as in claim 1, mounted on a motor vehicle, the signal being disposed adjacent the operator's station.

4. An out-of-time signal device for an internal combustion engine including an adjustable ignition distributor having distributor shaft actuated breaker points, an electric signal, an energizing circuit for the signal, a switch in the circuit, means responsive to actuation of the breaker points arranged to close the switch, a separate switch in the circuit, and means actuated by the distributor shaft arranged to close the separate switch simultaneously with said first named switch only when the distributor is out-of-time; the distributor including a breaker arm, and said first named switch including separate contact points, one of which is mounted on said arm.

5. An out-of-time signal device for an internal combustion engine including an adjustable ignition distributor having distributor shaft actuated breaker points, an electric signal, an energizing circuit for the signal, a switch in the circuit, means responsive to actuation of the breaker points arranged to close the switch, a separate switch in the circuit, a rotor on the distributor shaft, and rotor actuated means arranged to close the separate switch simultaneously with said first named switch only when the distributor is out-of-time.

6. An out-of-time signal device for an internal combustion engine including an adjustable ignition distributor having distributor shaft actuated breaker points, an electric signal, an energizing circuit for the signal, a switch in the circuit, means responsive to actuation of the breaker points arranged to close the switch, a separate switch in the circuit, a rotor on the distributor shaft, and rotor actuated means arranged to close the separate switch simultaneously with said first named switch only when the distributor is out-of-time; there being a normally fixed support adjacent the distributor, said separate switch being mounted on the support, and said other means including an actuating element of the separate switch projecting into the path of the rotor.

7. A signal device, as in claim 6, in which said support-mounted switch is adjustable relative to the distributor whereby to dispose said actuating element at a selective point in said path of the rotor.

8. An out-of-time signal device for an internal combustion engine including an adjustable ignition distributor having a driven distributor shaft, a body into which the shaft projects axially, a breaker arm in the body actuated from the shaft, and breaker points responsive to said arm; the device comprising an electric signal, a circuit for the signal, a switch in the circuit, said switch being mounted in the body and arranged to close in response to the breaker arm opening the breaker points, a separate switch in the circuit, and means actuated by the distributor shaft arranged to close the separate switch simultaneously with said first named switch only when the distributor is out-of-time.

9. An out-of-time signal device for an internal combustion engine including an adjustable ignition distributor having a driven distributor shaft, a body into which the shaft projects axially, a breaker arm in the body actuated from the shaft, and breaker points responsive to said arm; the device comprising an electric signal, a circuit for the signal, a switch in the circuit, said switch being mounted in the body and including one point on the breaker arm, such switch being arranged to close in response to the breaker arm moving to open the breaker points, a separate switch in the circuit, the distributor body being rotatably adjustable, a mount normally fixed relative to the adjustable body, the separate switch being mounted on the support, a rotor on the distributor shaft, and an actuating element of said separate switch projecting into the path of said rotor at a point such that the rotor causes closing of said separate switch simultaneously with closing of said first named switch only when the distributor is out-of-time.

10. A signal device, as in claim 9, including a fixed housing about a portion of the distributor shaft; said support being a bracket, and means securing the bracket to the housing in adjustable relation circumferentially of the distributor shaft.

11. An out-of-time signal device for an internal

combustion engine including an adjustable ignition distributor having distributor shaft actuated breaker points, an electric signal, an energizing circuit for the signal, a switch in the circuit, means responsive to actuation of the breaker points arranged to close the switch, a pair of separate switches interposed in parallel in the circuit in series relative to said first named switch, means mounting said separate switches adjacent the distributor, and means actuated by the distributor shaft arranged to close said separate switches in sequence as said shaft rotates; one or the other of said switches closing simultaneously with said first named switch only when the distributor is out-of-time.

12. An out-of-time signal device for an internal combustion engine including a distributor having a driven distributor shaft, a body into which the shaft extends axially, the body being adjustable about the shaft, a breaker arm mounted in the body actuated from the shaft, and breaker points in the body actuated by said breaker arm; the device comprising an electric signal, a circuit for the signal, a switch mounted in the body responsive to the breaker arm and arranged to close upon opening of the breaker points, said switch being interposed in the circuit, a rotor on the shaft, a separate switch in the circuit, means mounting the separate switch adjacent the distributor but independently of the adjustable body, and an actuating element of said separate switch projecting into the path of the rotor at a point such that the rotor causes closing of said separate switch simultaneously with closing of said first named switch only when the distributor is out-of-time.

13. A signal device, as in claim 12, in which said mounting means includes a bracket secured outside the body, the latter having a slot therein, and said actuating element of the separate switch projecting through the slot for rotor engagement.

14. A signal device, as in claim 13, in which the bracket is secured for adjustment circumferentially of the distributor shaft.

15. An out-of-time signal device for an internal combustion engine including a distributor having a driven distributor shaft, a body into which the shaft extends axially, the body being adjustable about the shaft, a breaker arm mounted in the body actuated from the shaft, and breaker points in the body actuated by said breaker arm; the device comprising an electric signal, a circuit for the signal, a switch mounted in the body responsive to the breaker arm and arranged to close upon opening of the breaker points, said switch being interposed in the circuit, a pair of separate switches connected in parallel in the circuit in series relative to said first named switch, a mount fixed relative to but adjacent the body, the latter having a slot therein, said separate switches being secured on the mount and including switch actuating elements projecting in adjacent but circumferentially spaced relation through the slot toward the shaft in the body, and a rotor on the shaft in the body including a part adapted to recurringly and successively engage said elements and close said separate switches, the closing of either of said switches simultaneously with the closing of the first named switch occurring only when the distributor is out-of-time.

16. A distributor timing indicator comprising in combination with a distributor which includes a distributor make and break arm operating the breaker points of the distributor, a separate nor-
